UNITED STATES PATENT OFFICE.

EDMOND THOMINE, OF PARIS, FRANCE.

STEAM-GENERATOR.

SPECIFICATION forming part of Letters Patent No. 723,337, dated March 24, 1903.

Application filed August 14, 1902. Serial No. 119,596. (No model.)

To all whom it may concern.

Be it known that I, EDMOND THOMINE, a citizen of the Republic of France, residing at No. 15 Rue de la Chaussée d'Antin, in the city of Paris, Republic of France, have invented certain new and useful Improvements in Steam-Generators, of which the following is a specification, reference being had therein to the accompanying drawings.

10 This invention relates to steam-generators, and is adapted for use with generators wherein the steam-supply is intermittent, as in sugar-refineries, steel-works, mines, &c. In the type of generator at present in use for such and similar purposes large water-space has been provided to insure safety, particularly in instances wherein the water and steam space is exposed to the direct action of the furnace-gases.

20 The present invention consists in providing a water reservoir or accumulator communicating with the steam-space of the generator and which is not exposed to the direct action of the furnace-gases and in which a supply of heated feed-water is maintained for a long period and utilized as a feed during the stoppage of the motor or apparatus using the steam without requiring a fresh supply of cold feed-water.

25 30 In the accompanying drawings, forming a part of this specification, the invention is illustrated in connection with the usual steam and water drums located above the generator, two of such drums being represented with an auxiliary drum or accumulator embodying the present invention.

Figure 1 represents a front view, and Fig. 2 a sectional side view, showing the pipe and valve connections.

35 40 1 and 2 are the usual steam and water drums, and 3 the accumulator-drum. The respective drums 1, 2, and 3 are in free communication by means of the pipes A, connecting at the top of each, as shown, and with the pipe B depending from the top of the accumulator-drum through its interior and connected to the horizontal perforated drum C. The pipes A receive the steam from the generator-drums 1 and 2 and convey it to the water-space in the accumulator 3 through the pipe B and perforated drum C. The steam therefore passes through the connections described

from the beginning of its formation and during the whole period of generation, and the water in the accumulator is thereby maintained at the temperature of the water in the generator. The steam-outlet is represented at V, Fig. 2, at the top of the accumulator-drum. The steam being taken for use from the accumulator and free from the vessel in which it is generated is comparatively dry.

45 The feed-water connections are arranged to feed at will directly into the generator-drums 1 and 2 through the admission-valve R, pipe D, check-valves E, and pipes F, or through the admission-valve R', pipe D', check-valve E', and pipe T into the accumulator-drum 3, and from the latter into the drums 1 and 2 through valve r, pipes d, and pipe t, or through both simultaneously. The elevated valve r is adapted to be operated from the fire-room by means of the connected wheel and chain s. The respective drums are shown filled to the normal level indicated by the valve-gages placed on the front of the drums, as shown in Fig. 1. When the motor or apparatus using the steam is started, the valves R, R', and r may be closed and no fresh feed admitted so long as the water-level in the drums 1 and 2 is above the lowest level permitted. At this point the feed is admitted through the valve r from the accumulating-drum 3 and continued until its complete exhaustion therefrom or down to a level adopted by the location of the valve r.

50 55 In Fig. 2 a partition k is shown in the accumulator-drum extending vertically to the level of the valve r and between the feed-outlet valve r inside the feed-pipe T to arrest the deposit of substances and salts entering through the pipe T or forming in the accumulator by reason of the equal temperature of the water with the temperature of the steam. With this partition the accumulator serves as a purifier, the precipitated salts 60 settling in the pocket and remaining there without danger of adhering, as the accumulator is not exposed to the action of the furnace-gases.

65 70 75 80 85 90 95 100 The size of the generator-drums and the accumulator can be varied to make the water-reserve as large as the requirements call for, and the invention may be adapted for use with any type of generator. It holds a large

reserve of water raised to the temperature of the steam itself and is not exposed to the action of the furnace-gases, and therefore not liable to explode, and at the same time serves to purify the feed-water.

Having thus fully described the invention, what is claimed is—

In combination with a steam-generator of an elevated accumulator-drum provided with the pipe A in open communication with the steam-space of the generator; a pipe B com-

municating with the pipe A and the water-space of the accumulator, an independent feed-water inlet and a feed-water outlet communicating with the water-space of the generator as set forth. 15

In testimony whereof I affix my signature in presence of two witnesses.

EDMOND THOMINE.
